UNITED STATES PATENT OFFICE.

AUGUST C. OHLE, OF NEW YORK, N. Y., ASSIGNOR TO HENRY H. BELL'S SONS, OF SAME PLACE.

DESIGN FOR NAPPED FABRIC.

SPECIFICATION forming part of Design No. 21,999, dated November 22, 1892.

Application filed September 8, 1892. Serial No. 445,388. Term of patent 7 years.

To all whom it may concern:

Be it known that I, AUGUST C. OHLE, a citizen of the United States, residing in the city, county, and State of New York, have invented and produced a new and original Design for Napped Fabrics, of which the following is a specification.

Figure 1 of the accompanying drawings shows a face view of a piece of the napped fabric ornamented according to my new design. Fig. 2 shows a cross-section of the ornamented napped fabric on the line 2 2 of Fig. 1.

This design is for a novel ornamentation of napped fabrics.

The leading feature of my design consists in a continuous unbroken undulating line having a napped appearance and showing upon the surface of the fabric, which fabric is also napped.

The design presents a waved or wavy appearance running irregularly over the fabric in a series of loops formed by the unbroken line, this series of irregular wavy unbroken loops forming the design.

In Figs. 1 and 2 of the drawings, the letters A A show the napped cloth, and the letters B show the continuous unbroken undulating line having the napped or wavy appearance and running over the fabric.

The letters C C in Fig. 1 show the loops or bends in the unbroken undulating line.

I claim—

The design for a napped fabric, as herein described and shown.

AUGUST C. OHLE.
